UNITED STATES PATENT OFFICE.

OTIS A. MYGATT, OF NEW YORK, N. Y.

DESIGN FOR A REFLECTOR.

No. 37,967.

Specification for Design.

Patented April 24, 1906.

Application filed July 14, 1905. Serial No. 269,728. Term of patent 14 years.

To all whom it may concern:

Be it known that I, OTIS A. MYGATT, a citizen of the United States, residing at New York, in the county of New York and State of New York, have invented a certain new, original, and ornamental Design for a Prismatic Glass Reflector, of which the following is a specification, reference being had therein to the accompanying drawings, forming part thereof.

Figure 1 is a side elevation of a prismatic glass reflector embodying my design. Fig. 2 is a perspective view from below, the prisms showing through the transparent medium being indicated by dotted lines.

The body of the reflector is composed of transparent glass and is covered externally below the top collar with reflecting-prisms, which are indicated by full lines in Fig. 1 and by dotted lines in Fig. 2, where they show through the body of the reflector.

I claim—

The ornamental design for a reflector of the form shown having external reflecting-prisms which are visible on the interior of the reflector, as described.

OTIS A. MYGATT.
